UNITED STATES PATENT OFFICE.

WILLIAM M. FINCK, OF DETROIT, MICHIGAN.

GARMENT.

1,132,768.

Specification of Letters Patent. Patented Mar. 23, 1915.

Application filed January 9, 1912. Serial No. 670,183.

To all whom it may concern:

Be it known that I, WILLIAM M. FINCK, a citizen of the United States of America, residing at Detroit, in the county of Wayne 5 and State of Michigan, have invented certain new and useful Improvements in Garments, of which the following is a specification, reference being had therein to the accompanying drawings.

10 The invention relates to the construction of garments and more particularly to overalls.

It is the object of the invention to overcome a defect in constructions as heretofore 15 used by reason of which the garment is frequently torn, and to this end the invention consists in the peculiar construction and arrangement of the reinforcement for the garment as hereinafter set forth.

20 In the drawings,—Figure 1 is an elevation of a portion of the garment to which my improvement is applied; Fig. 2 is a cross section on line $x-x$ Fig. 1.

A is a portion of a garment such as overalls, and B and C are the front and rear flaps at the waist which are separated by the placket D and are secured together by suitable means such as the buttons E engaging button holes F.

30 It frequently happens that in drawing on a garment of this character the foot is caught in the placket, with the result that the cloth is torn down. I have therefore devised an improved construction in which a reinforcement is employed for the cloth at the margin of the placket and which thereby avoids danger of tearing. This reinforcement may be applied in various ways, but as illustrated, G is a reinforcement member 35 which is stitched at the outer edge to the body of the garment adjacent to the placket

and which extends below the angle or lower end of said placket. As shown, this reinforcement extends beneath the edge of the back member H which is stitched thereto 45 and to the body of the garment. The result of this construction is the reinforcement of the placket edge of the flap C by two plies of material which greatly lessens the danger of tearing.

50 The reinforcement G may be made from waste scraps and as the labor of stitching it into the garment is very slight it will not materially increase the cost of production. This reinforcement G is preferably applied 55 only to the rear flap of the placket as this is the one which is in danger of being torn in the drawing on of the garment.

I is a pocket which has a portion overlapping and stitched to the reinforcing member.

60 What I claim as my invention is:

A garment provided with front and rear flaps forming the opposite sides of the placket, a reinforcing blank of substantially 65 trapezoidal form, the base of said blank extending below the placket and being stitched to the garment, said blank at one side being stitched for a portion of its length to one flap of the placket, its other side being 70 stitched throughout its entire length to the other flap, and a pocket constituting a reinforcing member stitched to the last mentioned flap and overlying said reinforcing strip and being stitched thereto.

75 In testimony whereof I affix my signature in presence of two witnesses.

WILLIAM M. FINCK.
